Primary Examiner — Ralf Seifert(74) *Attorney, Agent, or Firm* — IPLM Group, P.A.**CLAIM**

The ornamental design for a buckle portion, as shown and described.

DESCRIPTION

FIG. 1 is a front perspective view of a buckle portion constructed according to the principles of the present invention; FIG. 2 is a front view of the buckle portion shown in FIG. 1; FIG. 3 is a left side view of the buckle portion shown in FIG. 1;

FIG. 4 is a top view of the buckle portion shown in FIG. 1; and,

FIG. 5 is a bottom view of the buckle portion shown in FIG. 1.

The right side is a mirror image of the left side; and The rear side is a mirror image of the front side.

The broken lines showing portions of the buckle portion are for the purpose of illustrating portions that form no part of the claimed design.
